PROPORTIONAL MIXING TANK

Richard Beck, Jr., Minneapolis, Minn., assignor to McCulloch Corporation, Marine Products Division, Minneapolis, Minn., a corporation of Minnesota

Filed May 18, 1959, Ser. No. 813,919

8 Claims. (Cl. 220—86)

The present invention relates to containers and specifically to improved containers for proportionally mixing two fluids together.

Certain portable internal combustion engines, such as two-cycle outboard motors, require a fuel mixture of fixed proportions of oil and gasoline. Previously the desired mixture has been provided either by separately measuring the fluids to be mixed or in containers wherein a valve is provided either to permit fluid mixing or to permit receiving a limited amount of oil.

Accordingly this invention provides an improved and simplified proportional mixing tank. Two interconnected chambers are provided in the tank with one chamber being in fluid receiving relation to a tank spout. When the tank is on one side the spout opening prevents fluid communication between chambers providing for volumetric measuring of one fluid to be added to the tank in what is termed a "non-mixing" tank position. The tank is movable about a spout opposing corner to a second side whereon the chambers are in fluid communication permitting the mixing of the one fluid with a second fluid to be added in what is termed a "mixing" tank position.

These and other more detailed and specific objects will be disclosed in the course of the following specification, reference being had to the accompanying drawing, in which—

Fig. 1 is a front elevation view of a preferred embodiment of this invention and oriented in a non-mixing position.

Fig. 2 is a vertical sectional view taken in the direction of the arrows along line 2—2 in Fig. 1.

Fig. 3 is a vertical sectional view as in Fig. 2 but pivoted about one tank corner to a mixing position.

Fig. 4 is a vertical sectional view taken in the direction of the arrows along line 4—4 in Fig. 2.

Fig. 5 is a partially cutaway front elevational view of an alternate embodiment of this invention.

Fig. 6 is a vertical sectional view taken in the direction of the arrows along line 6—6 in Fig. 5.

With more particular reference to the accompanying drawing like numbers designate like parts and structural features in the various views. A preferred embodiment of this invention is illustrated in Figs. 1—4, wherein numeral 10 generally designates fluid holding tank housing with a carrying handle 12. A spout 14 adapted to removably receive a cap 15 is integrally mounted on 45° angled housing portion 16 between corner portions of adjacent longitudinal sides 17 and 18. Inside housing 10 a pair of dividers 20 have edge 21 spaced from adjacent side 18 forming a fluid passageway between narrow oil-measuring and gas-oil mixing chamber 22 and the rest of the housing 10 interior.

Dividers 20 have angularly diverging fluid deflecting portions 24 in fluid sealing relation to adjacent side 17 and angled portion 16 and are adapted to funnel fluid from spout 14 into the narrow mixing chamber 22. A baffle or deflecting plate 26 completes the tank input funneling section and extends in fluid sealing relation

2

from adjacent side 18 along portions 24 thence between dividers 20 extending partially through chamber 22. Plate 26 extends into chamber 22 at a 45° angle with respect to spout 14 for deflecting a fluid stream there-through toward side 17 and away from the aforesaid fluid passageways.

The operation of the preferred embodiment of this invention will now be described. Fig. 3 illustrates the tank in the initial and the normal carrying position with 10 the handle supporting side 17 upwards. The fluid passageways formed by dividers 20 and side 18 are now vertical, extending from the lowest side of the tank housing 10 upwardly to plate 26. The "old" gasoline-oil mixture in the tank has the same level in each of the tank chambers. With the tank being placed on a level spot it is pivoted on and about a spout diagonally opposing longitudinally extending corner portion 28 to the Fig. 2 or what may be termed a "non-mixing" position. Edges 21 now form the lower side of the fluid passageway and are above at least a portion of the spout 14 preventing fluid communication between chamber 22 and the rest of the tank interior. Now the old gasoline-oil mixture is held in the chambers in proportion to their respective fluid containing volumes, as will be hereinafter described, the chamber 22 volume being for measuring oil.

Cap 15 is removed from spout 14 and oil is poured therethrough until the oil level in chamber 22 reaches the lower lip portion of the spout. Chamber 22 now contains the oil-to-gasoline proportion of the old gasoline-oil mixture plus the newly added oil in amount sufficient to provide gasoline-oil mixture to finish filling the tank. The relation of the lower spout 14 lip portion to the tank together with the chamber 22 dimensions determines the chamber 22 fluid holding volume.

35 The empty fluid holding volume of the housing 10 interior is exactly the volume of gasoline needed to mix with the newly added oil in chamber 22 to finish filling the tank. Before adding the gasoline the tank is again pivoted about corner portion 28 back to the Fig. 3 or 40 what is termed a "fluid mixing" position with handle side 17 facing upwardly. Gasoline is now added through the spout 14 until the tank fluid level reaches a spout lower lip portion. The tank now contains a full amount of the desired gasoline-oil mixture.

45 As the gasoline was poured through the spout 14 it was deflected by plate 26 upwardly away from the passageway as indicated by the plate adjacent arrow in Fig. 3 creating a more turbulent flow for improved mixing and washing the oil from the chamber 22 sides of dividers 20. The gasoline turbulently flowed downwardly and through the passageway mixing with the oil to provide a uniform gasoline-oil mixture in the tank.

50 As the tank is carried by handle 12 the tank chambers are in continuous fluid communication permitting limited sloshing. The centrally located mixing chamber 22 acts as a baffle to limit the sloshing, making a partially filled tank easier to balance during carrying.

To pour the mixture from the tank, the tank is tipped to the left from the Fig. 3 position permitting the mixture 55 to flow through the spout 14 proportionately from each tank chamber.

With reference now to Figs. 5 and 6 there is illustrated an alternate embodiment of the present invention wherein the mixing chamber and the spout are moved from a longitudinal central tank location to a like longitudinal 60 end portion of the tank housing. In these two figures like numbers primed designate modified parts performing like functions in the preferred embodiment.

A spout 14 is integrally attached to angled portion 16' and disposed over a fluid funneling section for fluid communication with mixing chamber 22'. The chamber 22' is formed between a single divider or baffle 20' with a

side wall 30. An angularly extending deflecting plate portion 24' and a side funnel section 32 with a baffle plate 26' form the funnel section. In proportionately mixing two fluids in the alternate embodiment the same procedure is followed as described for the preferred embodiment wherein the tank is pivoted on and about a corner portion 28 diagonally opposite the spout.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A proportional mixing tank comprising a fluid holding housing having longitudinally extending adjacent housing sides with a spout therebetween and a spout diagonally opposing corner portion, the tank being pivotable about the corner portion between fluid mixing and non-mixing positions, a transversely extending divider inside the housing forming chambers on each side thereof and having one edge spaced from one of the said two housing sides for providing a fluid passageway between said chambers, the spout being effectively disposed to one longitudinal side of the divider such that it is communicatively connected with the one chamber and having its opening extending closer to the housing side opposite the one side than said one edge, and the passageway formed between said edge and one side extending transversely across the tank whereby at least a portion thereof is lower than said spout when the tank is resting on the side opposing the other adjacent side whereby the tank is in a mixing position.

2. A proportional mixing tank comprising a fluid holding housing having longitudinally extending corner portions and a spout centrally located along one of said corner portions, the housing being pivotable about a spout diagonally opposing corner portion between fluid mixing and non-mixing positions, a pair of transversely extending spaced apart dividers inside the housing forming a mixing chamber therebetween, funnel means interposed between the spout and the chamber for communicatively interconnecting same, the chamber being provided with passageway means extending transversely from the funnel means to a third corner portion along both dividers whereby when the tank is in a mixing position the passageway means serves to communicatively interconnect the chamber and the rest of the housing interior, and the spout having a lip portion extending toward a corner portion diagonally opposite the third corner portion whereby it is lower than said passageway when the housing is in a non-mixing position.

3. A proportional mixing tank comprising a fluid holding housing having longitudinal extending corner portions and a spout adjacent one longitudinal end, the housing being pivotable about a spout diagonally opposing corner portion between fluid mixing and non-mixing positions, a transversely extending mixing chamber inside the housing and immediately adjacent said one longitudinal end and provided with a transversely extending passageway opening to the rest of the housing interior, a funnel section inside the housing for communicatively connecting the spout and the chamber, deflecting means in the funnel section and disposed between the spout and passageway for causing fluid from the spout to move away from the passageway, and the spout having an opening portion extending lower than the passageway when the housing is in a non-mixing position.

4. A proportional mixing tank comprising a fluid holding housing having longitudinal extending corner portions, adjacent longitudinal housing sides with an angled portion therebetween with a spout formed therein, the housing being pivotable about a spout diagonally opposing housing corner portion between fluid mixing and non-mixing positions, a transversely extending mixing chamber inside the housing and provided with passage-

ways along one adjacent side and opening to the rest of the housing interior, funnel means in the housing for providing fluid coupling between the spout and the mixing chamber, a carrying handle on the other adjacent side, the spout having an opening extending lower than said passageways when the tank is in the non-mixing position whereby a limited volume of fluid may be added to the chamber through the spout, and the passageways being lower than said spout opening and the other adjacent side being upwardly when the tank is in the mixing position whereby the entire tank may be filled with fluid poured through the spout.

5. A proportional mixing tank comprising a fluid holding housing having longitudinal extending corner portions, adjacent longitudinal housing sides with an angled portion therebetween having a spout integrally associated therewith, the housing being pivotable about a spout diagonally opposing housing corner portion between fluid mixing and non-mixing positions, a transversely extending mixing chamber inside the housing and having a passageway along one of the adjacent housing sides opening into the rest of the housing interior, funnel means for providing fluid communication between the spout and the chamber and including a plate interposed between the passageway and the spout and extending into the chamber for deflecting fluid from said spout to move away from said passageway toward and along the other said adjacent housing side, and the spout opening extending toward the side opposing the one adjacent side such that it is closer thereto than the passageway opening.

6. A proportional mixing tank comprising a fluid holding housing having longitudinal extending corner portions, adjacent longitudinal housing sides with a longitudinal centrally located angled portion therebetween having a spout integrally associated therewith, the housing being pivotable about a spout diagonally opposing longitudinally extending corner portion between fluid mixing and non-mixing positions, a pair of transversely extending parallel spaced apart dividers longitudinally centrally disposed inside the housing and adjacent the spout, two deflecting plates inside the housing connecting the angled portion with each respective divider on opposite longitudinal sides of the spout, one edge of each of the dividers being spaced from one adjacent side for providing fluid communication between the chamber and the rest of the housing interior, a baffle plate extending in a contiguous relation with both deflecting plates away from said one adjacent side toward and beyond said divider edges for deflecting fluid from said spout to move toward and along the other said adjacent housing side, and the spout having an opening extending away from the one adjacent side further than the divider edge spacings therefrom such that when the tank one side is upward it is in a non-mixing position whereby the fluid level between the dividers is lower than the passageway as limited by the spout opening.

7. A proportional mixing tank comprising a fluid holding housing having a spout, a mixing chamber inside the housing which opens thereto along one side of the housing and disposed adjacent and being communicatively connected to the spout, a corner portion formed in the housing opposite the spout and adjacent a chamber portion opposite said opening, the tank being movable on the corner portion between fluid mixing and non-mixing positions, when the tank is in the non-mixing position the chamber opening extends horizontally and is higher than the lowest portion of the spout whereby fluid may be poured through the spout only into the chamber, and when the tank is in the mixing position the opening extends vertically for permitting a single fluid level in the tank.

8. A proportional mixing tank comprising a fluid holding housing having a spout opening, a mixing chamber inside the housing and extending to a housing portion op-

posite the spout and opening toward and spaced apart from a housing portion adjacent both the spout and the said opposite housing portion, a corner portion in the housing along the opposite portion remote from the adjacent portion, and about which the tank is pivotable between fluid mixing and non-mixing positions, the spout opening extending further away from the adjacent portion than the chamber is spaced therefrom, and funnel means inside the housing for communicatively connecting

the spout opening with the mixing chamber whereby any fluid entering or leaving the tank flows through the mixing chamber.
